Primary Examiner — Clare E Heflin(74) *Attorney, Agent, or Firm* — Marshall, Gerstein & Borun LLP(57) **CLAIM**

The ornamental design for a lighting fixture, as shown and described.

DESCRIPTION

FIG. 1 is a perspective view showing a new design for a lighting fixture angled rearward approximately 15 degrees from vertical;

FIG. 2 is a front view of the lighting fixture of FIG. 1;
FIG. 3 is a bottom view of the lighting fixture of FIG. 1;
FIG. 4 is a perspective view of the lighting fixture of FIG. 1 angled rearward approximately 30 degrees from vertical; and,

FIG. 5 is a perspective view of the lighting fixture of FIG. 1 angled rearward approximately 45 degrees from vertical. The broken lines shown on the drawings depict portions of the light fixture that form no part of the claimed design.
